UNITED STATES PATENT OFFICE.

EMIL STREHLER, OF STEIN, SWITZERLAND.

METAL CAP FOR ELECTRIC INCANDESCENT LAMPS.

1,157,057.

Specification of Letters Patent. Patented Oct. 19, 1915.

Application filed May 9, 1912. Serial No. 696,192.

To all whom it may concern:

Be it known that I, EMIL STREHLER, a citizen of the Swiss Confederation, residing at Stein, Switzerland, have invented certain new and useful Improvements in Metal Caps for Electric Incandescent Lamps, of which the following is a specification.

The metal caps for electric incandescent lamps of known construction comprising a cap which serves as support for the glass bulb of the lamp insulated from the contact cap have the inconvenience that they are very heavy owing to the insulating body. This circumstance not only increases the expenses connected with the transport of the lamps but it further increases the percentage of breakage caused by the vibrations resulting from the heavy weight. A further inconvenience connected with the manufacture of such lamps is that misfits very often happen owing to the insulating of the rim by the interposition of a glass body which has to be pressed in at the heated state.

This invention obviates the hereinbefore mentioned inconveniences by connecting the contact cap and the cap for the glass bulb by means of an insulating material which is deformable at the cold state.

In the accompanying drawings two forms of construction of the improved metal cap are shown by way of example.

Figure 1 represents the contact cap *a* open at the lower end and carrying the usual screw-contact. This cap *a* has at its open end two parallel flanges *b* and *c* between which a ring *d* is located which is made of insulating material such as insulating paper, india rubber or the like. The inwardly bent edge of the cap *e* designed to receive the glass bulb of the lamp is inserted in said insulating ring whereby this glass bulb is securely connected with the contact cap but perfectly insulated from the same. The ring *d* can further be composed of two or more separate rings for example of two annular disks made of card board and of an india-rubber ring placed against the contact cap and embracing the card board rings.

According to Fig. 2 the lower open end of the contact cap *a'* is telescoped into an upwardly projecting rim of the socket *e'* and rigidly connected with the same by

means of a collar *f*, an insulating ring *d'* being inserted between the contact cap and the socket. This insulating ring is of similar construction and material as the ring described with reference to Fig. 1 that is to say it is made of an insulating material which is flexible and deformable in the cold state such as for example card-board, india-rubber or asbestos.

I claim:

1. Metal cap for electric incandescent lamps, comprising in combination, a contact cap open at its lower end and provided at said end with a circular rim, a cap for the reception of the glass bulb provided at its upper end with a circular rim, the rim of one of said caps surrounding the adjacent rim of the second cap, and a ring of insulating material deformable in a cold state arranged between said two rims and held in place thereby.

2. Metal cap for electric incandescent lamps comprising in combination, a contact cap open at its lower end and having at said end a rim consisting of two parallel flanges, a ring of insulating material deformable in a cold state inserted between said two flanges, and a cap for the reception of the glass bulb provided with an inwardly bent upper rim sprung into said insulating ring to securely connect the cap for the glass bulb to the contact cap.

3. In an electric incandescent lamp, a cap or collar member for holding the smaller end of an incandescent bulb, one end of said collar having a continuous flange portion of less diameter than its body, a screw-threaded cap to be secured to said collar member, said screw-threaded cap having formed at one end thereof a continuous peripheral engaging portion in forced interfitting engagement with said flange, and an insulation deformable in the cold and clamped between said interlocking portions and held in place by the resiliency thereof.

In witness whereof I have hereunto set my hand in the presence of two witnesses.

EMIL STREHLER.
